UNITED STATES PATENT OFFICE.

FRANK RICHARD, OF SUNFIELD, MICHIGAN.

AXLETREE REPAIR IMPLEMENT.

SPECIFICATION forming part of Letters Patent No. 705,868, dated July 29, 1902.

Application filed April 18, 1902. Serial No. 103,638. (No. model.)

To all whom it may concern:

Be it known that I, FRANK RICHARD, a citizen of the United States, residing at Sunfield, in the county of Eaton and State of Michigan, 5 have invented certain new and useful Improvements in Axle-tree Repair Implements, of which the following is a specification.

My invention relates to improvements in appliances for recutting and repairing the 10 ends of buggy-axle-trees; and its objects are, first, to provide an implement with which the thread and shoulder on the end of an axle-tree may be repaired without the necessity of removing the axle-tree from the buggy, and, 15 second, to provide a means whereby the position of the cutters in the implement may be adjusted to insure the repair of the ends of the axle-trees without changing the length of the screw-bearing for the nut that holds 20 the buggy-wheel to place on the axle-tree. I attain these objects by the mechanism illustrated in the accompanying drawings, in which—

Figure 1 is an elevation of my appliance 25 applied to the end of an axle-tree with one arm of the frame cut away to show the relative position of the adjusting-clamps and of the cutting-tools. Fig. 2 is a right-hand end view, and Fig. 3 is a left-hand end view, of the 30 frame. Fig. 4 is an elevation of the frame with one form of my tool-adjusting attachment in place, and Fig. 5 is a plan of the adjusting device.

Similar letters refer to similar parts throughout the several views.

The frame of my implement consists of an annular base or support A, arranged to pass freely over the axle-tree and having arms B projecting back and turned in to unite and 40 form a cross at c. The inner diameter of the annular support A and the distance between the arms corresponding therewith is sufficient to admit of placing the clamps F, having the curved ends f, within them and around 45 the axle-tree G and leave sufficient space to allow of considerable variation of adjustment. These clamps are designed to be adjusted by the thumb-screws D and are designed, first, to perfectly center the frame 50 around the axle-tree; second, to hold the frame in perfect alignment with the axle-tree, for which purpose I prefer that one end of the

clamps bear upon the screw-threads g at the end of the axle-tree, as they are sure to be perfectly centered, while the balance of the 55 bearing-surface of the axle-tree may have become worn sufficiently to throw the cutters considerably out of center at some points; and, third, by setting the jam-nut d up solidly the end of the clamp may be made to assist 60 greatly in holding the end of the cutter E from trembling when cutting from the end of the axle-tree. The ends f of the clamps F are made concave to partly encircle the ends of the axle-trees, and the cutter E' should 65 pass through the body of the clamp or rest against the side of it, as indicated in Fig. 1, and the adjusting-screw D should pass through the clamp near the cutter, so that it would tend to hold it from sidewise motion, 70 so that with the adjusting-screw properly adjusted and the jam-nut solidly screwed to place the strength of the screw, together with the bearing of the end of the clamp upon the surface of the end of the axle-tree, will almost 75 wholly avert the danger of the cutter trembling when in use turning or cutting off the end of the axle-tree.

E' is a cutter for cutting off the end of the threaded portion g of the axle-tree to correspond with the amount cut from the shoulder g' and thus keep the threaded portion 80 the same length at all times.

e represents a rib or support in the arm B, so located that the back of the cutter E' will 85 be supported, thereby to support the cutter against the danger of trembling when cutting from the end of the axle-tree, as hereinbefore described.

The arm H is securely attached to the axle-tree by means of the bolt h or other suitable device, after which the frame A B is adjusted, as hereinbefore described, and the yoke I is placed in position, the ends passing through apertures in the ends of the arms H, a properly prepared bearing being passed over the journal C, which latter is integral with the frame-arms B. This yoke has a double office—first, to assist to hold the frame in proper alignment, and, second, to feed the frame along as the cutters do their work. The latter is attained by the proper manipulation of the nuts i, as may be readily understood by referring to Fig. 1. When the frame and yoke have been properly

adjusted upon the axletree, the crank J is secured to the end of the journal C, and the entire frame and its several parts are made to revolve around the axletree, when the 5 knives are brought into action by properly adjusting the yoke through the medium of the nuts *i*, as heretofore stated.

As the screw *g* is not of uniform length upon all axletrees, I find it desirable to provide for 10 adjusting one of the cutters, and have chosen the cutter E for the reason that to adjust the cutter E' would be likely to remove it from its support *e* and endanger its trembling, and thereby doing its work in an indifferent manner, and, further, there is not sufficient space 15 both sides of this cutter to successfully secure it if made adjustable. In Fig. 4 I have shown the cutter E supported in a detached cap B', having an aperture for the cutter to pass 20 through. This cap is so arranged that when securely bolted to the arm B by the bolts *b b* the cutter will be firmly held against the surface of the arm. The cap is preferably provided with a rib at each edge, as at *d' d'*, 25 that are so adjusted that they will closely embrace the opposite edges of the arm and hold the cutter as firmly edgewise against the pressure upon the end of the axletree as though it were held in a closely-fitting mortise 30 through the arm, as indicated in Fig. 1. This cap is provided with slotted apertures *b'* for the reception of the bolts *b*, so that it may be moved longitudinally to meet the necessary adjustment for the screw, as stated. 35 I do not desire to restrict myself to this particular means of supporting the adjustable cutter, but simply show it as one (a very convenient and perhaps the most available and most effective) means among several that 40 will be readily constructed by mechanics versed in the art to which it belongs. One reason why this appliance is perhaps better than other forms is that it insures a much longer bearing-surface for the cutter and to 45 that extent averts the danger of the cutter trembling when in use, as an adjustable cutter cannot well pass through the clamp F, as hereinbefore suggested in connection with a fixed cutter, and will need the additional support to lessen the danger of trembling. 50

The demand for an implement of this kind

arises from the fact that constant use of a buggy will cause the shoulder *g'* to wear back and allow the wheel to move endwise and cause a rattling or pounding of the parts, to 55 obviate which it is necessary to either, first, place a washer upon the axletree, or, second, to place new skeins in the hub of the wheel, either of which is objectionable, or to shorten the bearing portion of the axletree, 60 which would be expensive if necessary to remove the axletree from the buggy and do the work upon a lathe, while with this implement the work may be done very inexpensively and without the necessity of even removing the axletree from the buggy. 65

Having thus fully described my invention, what I claim as new, and desire to secure by Letters Patent of the United States, is—

1. In an implement for repairing axletrees, 70 an arm adapted to be secured to the axletree, a yoke connected with said arm and projecting back beyond the end of the axletree, a frame within said yoke and having a central bearing through the body of said yoke, adjustable clamps within said frame and arranged to center said frame with the axletree, adjusting-screws passing through the frame and said clamps, cutting-tools supported in said frame and having intermediate 80 supports between the frame and the axletree, substantially as and for the purpose set forth.

2. In an implement for repairing axletrees, 85 an adjusting-yoke adapted to be secured to the axletree, and having a central bearing, a frame having a central bearing engaging the central bearing of the yoke, said frame extending over the axletree longitudinally, clamps within said frame, adjusting-screws 90 actuating said clamps, a stationary cutter, an adjustable cutter, and a detachable and longitudinally-adjustable cap having an aperture for the cutter, and supporting-ribs, substantially as and for the purpose set forth. 95

Signed at Sunfield, Michigan, April 12, 1902.

FRANK RICHARD.

In presence of—

W. H. BENNETT,
E. F. PALMER.
